NEW YORK.

ARMREST FOR BANJOS.

Application filed June 19, 1926. Serial No. 117,010.

Our invention relates to certain new and useful improvements in arm rests for banjos and has for its object to provide an article of this character which is attractive in appearance and which is readily attachable to the instrument without dismantling the straining screws or other parts of the banjo.

We have accomplished this object by means of a construction hereinafter described and set forth in the claims, and illustratively exemplified in the accompanying drawing, in which, Figure 1 is a plan view of a banjo head equipped with our improved arm rest; Figure 2 is a side view of the same; Figure 3 is a fragmentary sectional view of the rim and supporting bracket for the arm rest taken on lines 3—3 of Figure 2; Figure 4 is a substantially transverse sectional view of the rim and arm rest taken on lines 4—4 of Figure 2; and Figure 5 is a transverse sectional view of a modified embodiment of the arm rest.

Referring to the drawings, 10 designates the banjo head comprising the usual rim 11, hoops 12 and straining screws 13, the latter being adjustable in brackets 14 carried radially of the rim 11. The usual arm 15 projects from the rim 11 at one side of the head 10 and disposed at the opposite side or bottom of the rim is a tail piece 16 from which the strings 17 project towards the arm 15.

The foregoing is a brief description of the usual banjo constructions, which vary only in the type and size of the straining screws and brackets, and in the distance between the screws. According to the present invention we have illustrated our improved arm rest on the left side of the tail piece 16, so as to afford all the necessary protection and support to the arm of the artist. The arm rest comprises a curved piece of metal 18, which is angular in cross section, and which is adapted to be superposed over the edge of the head 10, as illustrated in Figures 1 and 4. The rest is virtually composed of a side wall 19 and top plate 20, the former having a pair of spaced depending portions 21 provided with slots 22, which are adapted, when the rest is in place, to overlie two of the straining screws 13 at an elevation just above the position of the brackets 14, as illustrated in Figure 2. The portions 21 are utilized to secure the rest to the instrument and for this purpose we insert a screw 23 through each slot 22 to engage a clamping plate 24,

which comprises a straight mid-portion to receive the screw 23 and curved end portions 25, one thereof being adapted to partly embrace the adjacent straining screw 13 while the opposite one is drawn against the back of the portion 21, as illustrated in Figure 3. It will be clear that according to the clamping arrangement just described the arm rest may be accommodated to banjos having their straining screws of any length or distance apart.

The arm rest of this character is ordinarily finished by plating the same with a precious or semiprecious metal, e. g. nickel, gold or silver, and it has been found that after relatively short usage the plating wears off and exposes the base metal. This condition is particularly true of the surface of the head or top plate 20, because of the constant rubbing received by contact with the arm and sleeve of the artist. In order to avoid contact with the metal we propose to depress the inner surface of the top plate 20 to receive an insert 26 composed of a piece of fibre, celluloid, tortoise shell, pearl or any other suitable material. The insert 26, is a curved flat blank made to fit snugly in the depression 27 in the top plate, the marginal portion thereof being disposed at a height just below the top surface of the insert, as illustrated in Figure 4.

It will be clear that for use in connection with the cheaper grades of instruments, the depression in the top plate 20 and insert 26 will be omitted leaving a perfectly plain surface as illustrated in Figure 5.

To apply the arm rest according to the present invention, the slots 22 are brought into register with the straining screws selected to support the arm rest. A curved portion 25 of the clamp plate 24 is inserted behind the straining hook 13 and a screw 23 projected through the slot 22 and tightened in the clamp whereupon the latter secures the plate and screw or hook together. The essential advantage of the clamping arrangement, aside from the attaching feature, is in its possible vertical and lateral adjustment for the arm rest, since it is merely necessary to loosen the screws 23 in order to shift the whole rest to a higher or lower elevation and towards or away from the tail piece.

What we claim and desire to secure by Letters Patent is:—

1. An arm rest for a banjo having spaced straining screws disposed about the head, comprising an integral plate for the edge of the instrument, and means attachably connecting the plate to the straining screws and capable of peripheral adjustment with respect to the head to accommodate the spacing between screws. 35
5. An arm rest for a banjo comprising an angular plate curved from end to end to conform to the periphery of the banjo, one arm of the plate overlying the head of the instrument being recessed below the marginal portion of the arm, an insert of wear resisting material cut to conform to the shape of the recess in the arm and having a thickness substantially greater than the depth of the recess, said insert being disposed in said recess. 40
10. An arm rest for a banjo, comprising an integral plate for the edge of the instrument and having a recessed portion projecting over the head of the banjo, and an insert disposed in said recessed portion to accommodate the arm of the artist. 45
15. An arm rest for a banjo, comprising an integral plate for the edge of the instrument and having a recessed portion projecting over the head of the banjo, an insert disposed in said recessed portion to accommodate the arm of the artist, and clamping means operating to attachably and adjustably support the plate on the instrument. 50
20. An arm rest for a banjo, comprising an integral plate which is angular in transverse section and curved from end to end to conform to the periphery of the banjo, one portion of the plate being recessed and overlying the head of the instrument, an insert for said recess, the other portion of the plate having slotted projections disposed over the straining hooks of the banjo, and clamping means engaging the straining hooks and projections to attachably and adjustably support the arm rest on the instrument. 55
25. An arm rest for a banjo comprising an integral angular plate curved from end to end to conform to the periphery of the banjo, one arm of the plate overlying the rim of the instrument being provided with spaced projections having slots disposed longitudinally of the plate, said slotted projections overlying the straining hooks of the banjo, and clamping means operating to attachably and adjustably support the rest on the straining hooks, said means comprising screws adjustably disposed in the slots in the projection, and clamping plates to receive the screws and having their ends embracing the straining hooks to clamp the latter and projections together. 60
30. In testimony whereof we affix our signatures.

ALBERT D. GROVER.
LOUIS H. BERTRAM.
